UNITED STATES PATENT OFFICE.

FLOYD D. JAMES, OF SAN ANTONIO, TEXAS.

COMBINED ROLLER SKATE AND SCOOTER.

Application filed March 7, 1928. Serial No. 259,789.

This invention relates to improvements in skates of the two wheel type having one wheel at the front and another at the rear.

An object of the invention comprehends supporting members carried by the skate body and adapted to carry the wheels.

Another object of the invention contemplates foot plates adjustably mounted upon the body.

10 A further object of the invention embodies a bearing construction adapted to prevent binding action of the wheels.

With the above and other objects in view, the invention further consists of the following novel features and details of construction, to be hereinafter more fully described, illustrated in the accompanying drawings and pointed out in the appended claims.

In the drawings:—

20 Figure 1 is a side elevation of the invention as applied and in use.

Figure 2 is a top plan view of the invention.

25 Figure 3 is a longitudinal sectional view taken through the skate body.

Figure 4 are perspective views of the various parts which compose the skate body.

Figure 5 is a sectional view taken on line 5—5 of Figure 2.

30 Figure 6 is a sectional view taken on line 6—6 of Figure 2.

Figure 7 is a detail view taken on line 7—7 of Figure 1.

Referring to the drawings in detail,

35 wherein like characters of reference denote corresponding parts, the reference character 10 indicates a relatively flat elongated block or plate having spaced openings 11 extended horizontally therethrough from the side edges thereof.

40 Supporting plates, such as indicated at 12 are provided with a multiplicity of openings 13 adapted to coincide with the openings 11 in the block 10 when the same lie flush with the outer sides of

45 said block. Bolt members 14 are extended through the registering openings 11 and 13 of the block and supporting plate 12 respectively to sustain the latter in the positions

50 as best illustrated in Figure 1 of the drawings. Such connection will afford adjust-

ment to the supporting plates 12, whereby the same may be extended toward and away from the block to shorten or lengthen the skate body according to the various sizes of shoes.

The outermost ends of the supporting plates 12 terminate to provide upwardly and obliquely disposed extremities 15 having openings 16 adapted to accommodate the outermost ends of the axles 17.

Another object of the invention 55 is to provide wheels 18 preferably composed of rubber are adapted to receive centrally thereof, horizontally disposed exteriorly threaded sleeve members 19.

60 Roller bearings 20 surround that portion of the axles 17 within the sleeves 19. The intermediate portion of the axles 17 are grooved, as indicated at 21, and within which a quantity of lubricant may be retained and fed to the roller bearings 20.

65 Jam nuts 22, carried upon the outermost ends of the sleeves 19, are adapted to abut face plates 23 engaging the opposite faces of the wheels 18 circumferentially of the sleeves 19. Shoulders 24, formed adjacent the ends of the axles 17 and beyond the ends of the sleeves 19, are adapted to abut washers 25 which space the outwardly and upwardly 70 obliquely disposed extremities 15 of the supporting plates 12 whereby binding action between the sleeves 19, the roller members 20 and the washers 25 will be obviated.

75 The particular type of bearing will also prevent wobbling, weaving and swaying of the wheels. In addition, I have provided bottom plates 26 having openings 27 disposed axially of the longitudinal centers thereof and which are adapted for registration with correspondingly disposed openings 28 in the block 10. Heel and toe plates 29

80 and 30 respectively, carried upon the upper side of the block 10, are adapted to receive bolt members 31, which extend through the registering openings 27 and 28 in the bottom plates 26 and block 10.

85 The construction evolved from the foregoing description and accompanying drawings will afford adjustment to the skate body to extend and retract the wheels, and to regulate the heel and toe plates commensu-

rate with the particular sides of the skater's foot.

An arcuate-shaped counter plate 32, up-standing from the rear portion of the heel plate 29, is adapted to engage the counter and heel of the skater's shoe. Straps or other fastening devices being carried upon the heel and toe plates 29 to secure the skater's shoe upon the skate.

10 Wear plates, such as indicated at 33, are adapted to lie flush against the outer sides of the block to insulate same from the supporting arms 12. Said plates are furthermore provided with openings to accommodate the adjacent ends of the bolt members 14.

15 The invention is susceptible of various changes in its form, proportions and minor details of construction, and the right is here-20 in reserved to make such changes as properly fall within the scope of the appended claims.

Having described the invention, what is claimed is:

1. A skate comprising an elongated block 25 having a multiplicity of vertically and horizontally disposed openings therein, supporting plates carried by the block and having openings registering with the horizontally disposed openings in the block, fastening ele-30 ments passed through the horizontally disposed openings in the block and supporting plates, heel and toe plates carried upon the upper side of the block, bottom plates ar-35 ranged upon the underside of the block, the heel and toe plates and bottom plates being provided with openings registering with the vertical openings in the block to receive fastening elements, the outermost ends of the supporting plates being outward-40 ly and upwardly obliquely disposed, and wheels journaled between the obliquely disposed ends of the supporting plates.

2. A skate construction comprising an elongated block having vertically and trans-45 versely disposed openings, heel and toe plates carried upon the upper sides of the block, bottom plates arranged upon the underside of the block and joined with the heel and toe plates through the vertical openings in 50 the block, and supporting plates carried upon the sides of the block and between the adjacent faces of the heel and toe plates and the bottom plates, the outermost ends of the supporting plates terminates to provide 55 outwardly and upwardly obliquely disposed extremities, and wheels journaled between the ends of the supporting plates.

In testimony whereof I affix my signature.
FLOYD D. JAMES.
